MACHINE TOOL

Louis F. Polk, Dayton, Ohio, assignor to The Sheffield Corporation, Dayton, Ohio, a corporation of Ohio

Application April 26, 1943, Serial No. 484,580

18 Claims. (Cl. 125—11)

This invention relates to grinding machines and more particularly to means for truing or surfacing the grinding wheel of such a machine.

One object of the invention is the provision, in a grinding machine, of a grinding wheel truing device including a rotatable crusher wheel having supporting and control means whereby the crusher wheel is moved automatically into contact with the grinding wheel and is then given a comparatively slow feeding movement into the grinding wheel for truing the surface of the grinding wheel.

Another object is the provision of a rotatable crusher wheel adapted to operate in peripheral contact with the grinding wheel to true the surface of the grinding wheel, in combination with an adjusting motor which operates to move the crusher support in a controlled manner so that the crusher wheel is brought rapidly into a predetermined position in which it contacts with the grinding wheel and is then fed into the grinding wheel for effective crushing action.

Another object is the provision of a crusher wheel support carried by the frame of a grinder, and a motor which automatically controls a sequence of operations, first lowering the crushing wheel into contact with the grinding wheel, then starting the grinding wheel into operation, then feeding the crusher wheel slowly towards the axis of the grinding wheel, and then backing off the crusher wheel.

Other objects and advantages of the invention will be apparent from the following description, the appended claims, and the accompanying drawing, in which,

Fig. 1 is a side elevation, partly in section, showing the upper portion of the machine frame of a grinder, and the adjusting and operating means for the crusher support;

Fig. 2 is a vertical section on a reduced scale, on the line 2—2 of Fig. 1;

Fig. 3 is a view showing the arrangement of the double lift cam;

Fig. 4 is a detail of the feed ratchet operating mechanism;

Fig. 5 is a detail showing the timing cam and its switch;

Fig. 6 is a detail showing the clutch retaining pawl and cam;

Fig. 7 is a detail showing the ratchet wheel and the clutch release pawl;

Fig. 8 is a diagrammatic showing of the electrical connections; and

Fig. 9 is a sectional partly diagrammatic view showing the grinding wheel, its support, and the

driving means by which it is operated at comparatively slow speed.

Referring more particularly to the drawing, in which the same reference numerals designate like parts in the several views, 10 designates the frame of a grinding machine, having a rotatable grinding wheel 11 arranged for rotation in the frame. The wheel 11 is rotated at comparatively high speed by a suitable driving motor which has not been illustrated since a power drive of a grinding wheel is very well known in the art. Where the grinding wheel is stationary, the frame 10 forms a part of the fixed main frame structure of the grinding machine, although if the grinding wheel is axially movable in operation, or is movable towards and from the work, the frame 10 will constitute the movable support for the wheel as is well known in the art. The grinding wheel as herein shown is one having a series of annular ribs so formed as to grind threads as the work-piece is moved axially with relation to the grinding wheel.

The grinding wheel after a period of use should be trued, and this truing operation has been accomplished by moving diamonds along the wheel surface to give the desired contour, or by manually moving a rotatable metal crusher having annular ribs that give the desired contour on the grinding wheel.

30 In accordance with the present invention, the rotatable crusher wheel shown at 12 is adapted for free rotation in a crusher wheel supporting bracket 13 and normally, when the grinding wheel is in use, the crusher 12 is arranged some little 35 distance radially outwardly from the grinding wheel. This crusher may be of suitable hard metal so that when it is pressed against the grinding wheel, with the grinding wheel rotating at comparatively slow speed, the crusher will be revolved by the grinding wheel and will press or 40 crush the desired surface on the grinding wheel to bring the latter back to a true form.

The crusher wheel supporting bracket 13 is 45 slidably guided in side walls 15 of frame 10, and is adjustably secured to a slidable plate 16 carrying a head 17 which is connected by adjusting screw 18 to a nut 19 fixed on the supporting bracket. The plate 16 is guided for movement towards and from the axis of the grinding wheel 11 between the supporting bracket 13 and the wall portion 21 of the frame, and it projects up through an opening in the upper portion of the frame which is large enough to receive the head 17 although the latter is normally arranged above the 50 frame as shown in Fig. 1. The upper portion of

the screw 18 has a square head 22 so that it can be turned by a wrench to raise or lower the supporting bracket 13 with respect to the head 17 and the plate 16. A scale 30 on the head 17 and a cooperating post 30' on the frame 10 show the position of the head and can be used to determine if the head is at its lowermost position.

As shown, the crusher is arranged up above the grinding wheel, and the movements of the crusher wheel support take place vertically and transversely of the axis of the grinding wheel.

The wall portion 21 of the frame has a vertical slot that receives a bar 23, fixed to the plate 16 by pins 24, and having studs 25 projecting out beyond the wall portion 21 and connected together by a plate 26 which rotatably carries a pair of rollers 27, one on each side of the plate. These rollers are operated by a double plate cam having cam portions 28 and 29 which positively control the up and down movement of plate 26 and consequently control the up and down movement of the plate 16 and head 17. In the absence of any rotation of the screw 18, the crusher supporting bracket will also move up and down with the plate 16.

The cams 28 and 29 are power operated in an automatic manner to advance the crusher towards the grinding wheel at a comparatively rapid rate, and then hold the plate 16 and the head 17 stationary during the crushing operation. After the crushing operation is completed plate 16 and head 17 are moved up to their original positions by the cams so that the crusher is spaced from the grinding wheel. After the crusher has been lowered by the cams 28 and 29, and while the plate 16 remains stationary in its lowered position, the adjusting screw 18 is automatically turned so that the crusher will be slowly fed into the grinding wheel, and the actual crushing operation takes place at a controlled rate. The extent of movement given to the crusher wheel supporting bracket by the adjusting screw 18 may be such as to move the crusher a few thousandths of an inch while the grinding wheel rotates through several revolutions, the rotation of the grinding wheel rotating the crusher wheel itself.

The construction herein shown as a preferred embodiment of the mechanism for automatically moving the crusher wheel during the crushing operation will now be further described. The frame 10 carries an adjusting motor 31, preferably an electric motor having a gear reducing drive 32 to a short shaft 33. Fixed on the shaft 33 is a ratchet wheel 34 adapted to be coupled to the drive plate 35 by a pawl 36 pivoted at 37 on the drive plate. A spring 38 tends to connect the pawl to the drive plate although a clutch release pawl 39 controlled by a spring 40 normally holds the upwardly extending portion of pawl 36 towards the right as viewed in Fig. 7 and keeps the pawl 36 free from the ratchet wheel. By energizing a relay or solenoid 42, the free end of the clutch release pawl is pulled down and this frees the pawl 36 so that the ratchet wheel is placed in driving connection with the drive plate 35. The drive plate 35 can be rotated through one revolution and then its cam projection 43 comes up against the finger 44 on the end of the clutch release pawl and this finger positively stops the rotation of the drive plate 35. Just before this takes place however the upwardly projecting portion of the pawl 36 comes against the finger 44 and is forced out of engagement

with the ratchet wheel to disconnect the driving force from the drive plate.

The drive plate 35 is fixed on a shaft 46 rotatably journaled in bearing portions 47 of the frame 10. The shaft 46 is also provided with a cam 48 which controls a clutch retaining pawl 49 serving to open and close the motor switch 51 and thus control the starting and stopping of the adjusting motor 31.

Another cam 52 on shaft 46 serves as a timer to control a switch 53 which controls a motor 56 which is employed during the crushing operation to provide a comparatively slow speed drive for the grinding wheel 11. When the switch 53 is closed it operates through a relay 54 to close switch 55, see Fig. 8, and cause the grinding wheel 11 to rotate at comparatively slow speed.

Cam 57 on shaft 46 controls the feed screw 18 through lever 58, the upper end of which bears against a vertically extending plate portion 59 of a ratchet feed yoke 60 arranged for rotation on the upper portion of the feed screw 18. The feed yoke is thus given an oscillatory movement under the control of the feeding cam 57. The feed yoke pivotally carries a feed pawl ratchet 61 which operates against the ratchet wheel 62 fixed on the feed screw 18. The feed movement takes place as the ratchet pawl is carried to the right as viewed in Fig. 2, to produce a lowering movement of the crusher wheel bracket 13 with respect to the plate 16 and the head 17.

Suitable means is provided for adjusting the amount of feed movement imparted to the screw 18, to permit movement of the crusher wheel into the grinding wheel to an extent dependent upon the wheel characteristics, the pitch spacing of the wheel ribs, etc. For this purpose, the lever 58 is provided with an extensible arm formed of adjustably interconnected arm sections 70 and 71, one of which is slotted as indicated at 72. A securing bolt or screw 73 operable along the slot 72 holds the two arm sections rigidly to one another and permits adjustment in the length of the arm and consequently permits adjustment in the amount of movement imparted to the plate portion 59 for any rotation of the cam 57. The amount of movement of the plate portion 59 may also be controlled, for varying the amount of feeding movement, by laterally adjusting the upper end portion 74 of the lever 58, with respect to the arm section 71, the upper portion of arm section 71 being turned out as shown in Fig. 1 and adjustably supporting the foot portion 75 of the portion 74 as by means of a securing screw 76 operable along a slot in the outturned upper portion of the arm section 71. This provides variation in the distance between the axis of the screw 18 and the point of application of force to the plate portion 59. As will be noted in Fig. 1, means is also provided for indicating, to the operator, the amount of feeding movement imparted to the screw 18, this means comprising index marks 77 on a dial 78 which is fixed to the screw 18 by means of a set screw 79. The indications or scale markings 77 act in conjunction with an index mark 80 on the nonrotatable head 17.

As will now be apparent, when the operator desires to crush or true the grinding wheel, and the device has previously been properly set up, he closes the starting switches shown at 64 in Fig. 8, and this energizes the solenoid 42 from the power source 65. The solenoid pulls the clutch release pawl 39 so that its finger 44 releases pawl 36 and permits that pawl to drop in-

to the ratchet wheel 34. At the same time lever 39 is moved, it closes the motor switch 51 so that the motor 31 is energized through connection 66 to source 65. In circuit with motor 31 is a normally closed stopping switch 68. The ratchet wheel thus starts turning, carrying the drive plate 35 along with it, and during the 360° movement of the drive plate the following operations take place successively.

First, the double plate cam 28 and 29 causes the crusher wheel support to be lowered until the crusher wheel is engaging the grinding wheel 11. This is completed in about 50° travel of shaft 46. Then the timing cam 52 closes switch 53 to cause rotation of the motor 56 to operate the grinding wheel at a comparatively slow speed, through about 200° movement of the feeding cam or from point *a* to point *b*, see Fig. 4, so that the ratchet pawl 61 turns the ratchet wheel 62 slowly and thus slowly rotates the adjusting screw 18 in a positive manner during the effective crushing operation, the movements of the adjusting screw causing the crusher wheel to be forced positively and in a controlled manner against the crusher wheel and exert the desired pressure in the crushing operation. The arrangement is such that the grinding wheel rotates through several revolutions as the cam 57 rotates about 200°, degrees. Between the points *b* and *c* on the cam 57 the cam surface is concentric with its axis so no feed movement of the screw 18 is produced as the grinding wheel rotates one or two revolutions before retracting the crusher. After the feed-in of the crusher wheel stops and as the point *c* on cam 57 comes opposite the roller on lever 58, the double plate lift cam 28 and 29 moves the whole crusher support upwardly, comparatively rapidly, without however disturbing the adjustment between the screw 18 and the crusher supporting bracket. During this upward movement of the crusher wheel support, the arm 58 is spring returned in a counter-clockwise direction ready for the next ratcheting step. Before the upward movement of the crusher wheel support is completed the motor 56 which drives the grinding wheel during the crushing operation is deenergized under the control of the timing cam 52. The cam shaft then completes its 360° of travel and is latched at the completion of its travel. Just before it is latched the clutching pawl 49 drops into a notch in cam 48 and opens the motor switch 51. These several operations take place successively at the proper times so that the crusher will be brought against the grinding wheel when the grinding wheel is not rotated, and after the grinding wheel starts to move, the in-feeding movements of the crusher are carried out automatically in a controlled manner. When a second crushing cycle takes place, there will of course be a further in-feeding movement causing a further adjustment in the relative positions of the crusher bracket 13 and the plate 15.

After the wheel has been considerably reduced in diameter and it is necessary to replace it with a new wheel the feed ratchet pawl 61 may be held out of engagement with ratchet wheel 62, and the adjusting screw 18 operated manually by a wrench applied to its square head 22 so that the bracket 13 is moved upwardly to a desired initial position so coordinated with the diameter of the new grinding wheel that it will contact the grinding wheel when it is lowered by the cam 28-29. The adjusting screw 18 can be turned manually at any time during the crushing operation if that should be desired.

When a new wheel, that has not been previously grooved, is applied to the machine, the crusher wheel supporting bracket 13 is moved up far enough, by turning the screw 18, so it will not quite touch the grinding wheel when the head 17 is lowered by the crusher wheel adjusting motor. The crusher adjusting motor is then started and when a resulting cycle is only partly completed, the switch 68 is opened, to stop the adjusting motor 31 at a time when the crusher supporting bracket is in its lowermost position. The switch 68 is opened manually after the switch 53 is closed, so that the grinding wheel is rotated by motor 56. The crusher wheel is engaged with the grinding wheel and is forced into the grinding wheel by manually turning the screw 18 until the groove of the grinding wheel is completed. The switch 68 is then closed again so that the balance of the crushing cycle is completed, leaving the crushing wheel finally in its elevated position and ready for a succeeding crushing cycle.

While the form of apparatus herein described constitutes a preferred embodiment of the invention, it is to be understood that the invention is not limited to the precise form herein disclosed, and that changes may be made therein without departing from the scope of the invention which is defined in the appended claims.

What is claimed is:

1. A grinding machine having a frame carrying a rotatable grinding wheel and driving means therefor; a rotatable crusher wheel, a crusher wheel support movably carried by the frame, a feed screw for positively controlling the position of said support, an adjusting motor, and means operable to cause the adjusting motor to move the crusher wheel support rapidly to the grinding wheel, then to operate said feed screw to feed the crusher support slowly through a predetermined distance to the grinding wheel and then retract it from the grinding wheel.

2. A grinding machine having a frame carrying a rotatable grinding wheel and driving means therefor, a rotatable crusher wheel, a crusher wheel support movably carried by the frame, an adjusting motor, means operable to cause the adjusting motor to move the crusher wheel support rapidly to the grinding wheel, then to feed said support slowly to the grinding wheel and then retract it from the grinding wheel, and means for initiating slow speed rotation of the grinding wheel before the slow feeding movement of the crusher wheel support takes place.

3. In a grinding machine having a frame carrying a rotatable grinding wheel and driving means therefor, a rotatable crusher wheel, a crusher wheel support movably carried by the machine frame, a carrier movably mounted on the frame and carrying the crusher wheel support, adjusting mechanism including an adjusting motor for varying the position of said support on the carrier, and means operated by said motor for moving the carrier to move said crusher wheel to the grinding wheel.

4. In a grinding machine having a frame carrying a rotatable grinding wheel and driving means therefor, a rotatable crusher wheel, a crusher wheel support movably carried by the machine frame, a carrier movably mounted on the frame and carrying the crusher wheel support, adjusting mechanism for varying the position of said support on the carrier and including means operable to move the carrier rapidly towards the grinding wheel, then maintain the carrier in a

predetermined position for a time and then retract it from the grinding wheel, and means for automatically feeding the crusher wheel towards the grinding wheel while the carrier remains in said predetermined position.

5. A grinding machine having a frame carrying a rotatable grinding wheel and drive means therefor, a rotatable crusher wheel, a crusher wheel support movably carried by the frame, a plurality of adjusting mechanisms for said support, an adjusting motor for operating said mechanisms, and means for automatically operating said mechanisms sequentially by the adjusting motor to bring the crusher wheel into engagement with the grinding wheel and then slowly feed the crusher wheel into the grinding wheel.

6. A grinding machine having a frame carrying a rotatable grinding wheel and drive means therefor, a rotatable crusher wheel, a crusher wheel support movably carried by the frame, adjusting mechanism for said support, an adjusting motor, a one revolution clutch between the adjusting motor and the adjusting mechanism, and means driven by said motor for positively moving the crusher wheel support to engage the crusher wheel with the grinding wheel and then feed the crusher wheel slowly towards the grinding wheel.

7. A grinding machine having a frame carrying a rotatable grinding wheel and drive means therefor, a rotatable crusher wheel, a crusher wheel support slidably guided on the machine frame and comprising a bracket movable towards and from the grinding wheel axis and a reciprocably operable carrier slidably guided on the machine frame for movement towards and from the grinding wheel axis and slidably supporting said bracket, power means for reciprocating said carrier on said frame, a threaded interconnection between the carrier and the bracket, means for manually operating said interconnection, and a connection to said power means for automatically operating said interconnection to feed the crusher wheel into the grinding wheel.

8. A grinding machine having a frame carrying a rotatable grinding wheel and drive means therefor, a rotatable crusher wheel, a crusher wheel support movably carried by the machine frame, adjusting mechanism for said support, an adjusting motor for operating said adjusting mechanism, said adjusting mechanism including a feed screw and a pawl and ratchet for said feed screw, and means operated by said adjusting motor to move the crusher wheel support towards the grinding wheel and subsequently operate the pawl and ratchet to feed the crusher wheel into the grinding wheel.

9. A grinding machine having a frame carrying a rotatable grinding wheel, power means for rotating the grinding wheel at a speed less than a normal grinding speed, a rotatable crusher wheel, a crusher wheel support movably carried by the machine frame, adjusting mechanism for said support, an adjusting motor for operating said adjusting mechanism to move the crusher wheel to the grinding wheel and means controlled by said adjusting motor to operate said power means after the crusher wheel is moved into contact with the grinder wheel.

10. A grinding machine having a frame carrying a rotatable grinding wheel, power means for rotating the grinding wheel at a speed less than a normal grinding speed, a rotatable crusher wheel, a crusher wheel support movably carried by the frame, an adjusting motor, means operated

by said adjusting motor to move the crusher wheel support rapidly towards the grinding wheel, to initiate slow speed operation of the grinding wheel by said power means, to then move the crusher wheel slowly to the grinding wheel and to then retract it from the grinding wheel, means for manually moving the crusher wheel towards the grinding wheel, and means to stop the motor controlled movements of the crusher wheel while the power means is rotating the grinding wheel to permit movements of the crusher wheel under manual control.

11. In a grinding machine having a frame carrying a rotatable grinding wheel, driving means for said grinding wheel, a rotatable crusher wheel, a crusher wheel support movably carried by said frame, a carrier movably mounted on said frame and carrying the crusher wheel support, adjusting mechanism for varying the position of said support on the carrier, additional adjusting mechanism for varying the position of the carrier on the frame, an adjusting motor for operating said adjusting mechanism, means for varying the amount of movement of the crusher wheel support, and indicating means for showing the position of the crusher wheel.

12. A grinding machine having a frame carrying a rotatable grinding wheel, driving means for operating said grinding wheel at a speed less than a normal grinding speed, a rotatable crusher wheel, a crusher wheel support movably carried by the frame, a power source, adjusting mechanism operated from said source to advance the crusher wheel support towards the grinding wheel, means operable at the completion of such movement to initiate operation of said driving means, means including a power operated adjusting screw for positively feeding the crusher wheel support slowly towards the grinding wheel during operation of said driving means, and means for stopping feeding movement of the crusher wheel support during continued operation of said driving means before the crusher wheel support is retracted.

13. A grinding machine having a frame carrying a rotatable grinding wheel, driving means for operating said grinding wheel at a speed less than a normal grinding speed, a rotatable crusher wheel, a crusher wheel support movably carried by the frame, a power source, adjusting mechanism operated from said source to advance the crusher wheel support rapidly towards the grinding wheel, means operable at the completion of the rapid movement of the crusher wheel support to initiate operation of said driving means, means including a power operated adjusting screw for positively feeding the crusher wheel towards the grinding wheel slowly during the operation of said driving means, power operated means for retracting the crusher wheel support, and means insuring a delay after completion of the feeding movement of the crusher wheel before retraction of the crusher wheel is initiated.

14. A grinding machine having a frame carrying a rotatable grinding wheel, driving means for operating said grinding wheel at a speed less than a normal grinding speed, a rotatable crusher wheel, a crusher wheel support movably carried by the frame, power means for adjusting said crusher wheel support, and means controlling said power means to automatically and sequentially provide rapid approach of the axes of the crusher wheel and the grinding wheel, then initiate operation of said driving means, then provide slow approach of the axes of the crusher

wheel and the grinding wheel, then maintain the axes of the grinding wheel and the crusher wheel at a fixed spacing during continued operation of the driving means and then separate the crusher wheel and the grinding wheel.

15. A grinding machine having a frame carrying a rotatable grinding wheel, driving means for operating said grinding wheel at a speed less than a normal grinding speed, a rotatable crusher wheel, a crusher wheel support movable relatively to the grinding wheel in a direction to vary the distance between the axes of the crusher wheel and the grinding wheel, and means for automatically in timed sequence first moving the crusher wheel support and grinding wheel relatively to cause approach of the axes of said wheels and then initiate operation of said driving means.

16. A grinding machine having a frame carrying a rotatable grinding wheel, driving means for operating said grinding wheel at a speed less than a normal grinding speed, a rotatable crusher wheel and means for automatically and sequentially causing approach of the axes of said wheels at a comparatively rapid rate, then initiate operation of said driving means, and then causing further approach of the axes of said wheels at a comparatively slow rate.

17. A grinding machine having a frame carrying a rotatable grinding wheel, driving means for operating said grinding wheel at a speed less than a normal grinding speed, a rotatable crusher wheel, a crusher wheel support carried by said frame, power means for adjusting said crusher wheel support relatively to the grinding wheel

axis and in a direction towards and from the grinding wheel, a positive mechanical operating device for moving the crusher wheel support, and means operable to cause said power means to 5 carry out a cycle of operations to sequentially cause the crusher support to be moved towards the grinding wheel at a comparatively rapid rate, then cause operation of said mechanical interconnection to move the crusher support at a comparatively slow rate, and then maintain the axes of said wheels with a fixed spacing and then separating the crusher wheel from the grinding wheel.

18. A grinding machine having a frame carrying 15 a rotatable grinding wheel, driving means for operating said grinding wheel at a speed less than a normal grinding speed, a rotatable crusher wheel, a crusher wheel support, a slide mounted on said frame for movement towards and from 20 the grinding wheel and carrying said crusher wheel support for movement thereon towards and from the grinding wheel, power means for adjusting said crusher wheel support on said slide and for adjusting said slide on said frame, and 25 means controlling said power means to sequentially move the crusher wheel support rapidly towards the grinding wheel, then initiate operation of said driving means, then feed said support slowly towards the grinding wheel, then 30 maintain the grinding wheel support in fixed position during continued operation of the driving means and then retract the crusher wheel support.
